Atty.

UNITED STATES PATENT OFFICE.

CIRILL J. STEINER, OF CLEVELAND, OHIO.

KEY-RETAINER.

1,242,257.

Specification of Letters Patent. Patented Oct. 9, 1917.

Application filed April 25, 1917. Serial No. 164,339.

To all whom it may concern:

Be it known that I, CIRILL J. STEINER, a citizen of the United States, residing at Cleveland, in the county of Cuyahoga and State of Ohio, have invented certain new and useful Improvements in Key-Retainers, of which the following is a specification.

This invention relates to a key retaining device for use on doors for preventing tampering with the lock from the exterior. The ordinary lock having a key hole providing an opening entirely through the door is practically no safe-guard even after being locked, if not protected by some auxiliary device. The primary object of the present invention is the provision of a key retainer adapted to attachment to the shank of the door knob on the interior of the door and to receive the head of the key, to prevent the turning of the key from the opposite side of the door to which it is inserted, and also preventing the tumbling of the key from the lock.

A further object of the invention is to provide a device for the purpose set forth that is readily adjustable, universally, to accommodate keys of different sizes, and to fit varying conditions or positions of fixtures with which the device co-operates to perform its functions.

A further object of the invention is the provision of a simple, inexpensive and durable device that is highly efficient for its intended purpose or use. With these objects in view the invention consists of certain novel features of construction, combination and arrangement of parts as will be fully described and definitely pointed out in the claims.

In the accompanying drawings forming a part of the specification, Figure 1 illustrates the application of the improved device to a door.

Figs. 2 and 3 are views of the device looking from the left and right, respectively, of Fig. 1.

Fig. 4 is a plan view of the supporting member.

Fig. 5 is an under-side view of the key engaging member detached, and Fig. 6 is an under-side view of the supporting member.

Throughout the drawings and description similar characters of reference are employed to designate similar parts.

The construction of the improved device

provides for three co-operating members adjustably connected by two set-screws, forming a combination of five elements that operate conjointly with the door knob fixtures and the key to retain said key in the lock 60 and prevent the turning of same.

A supporting bracket 1, right angular in formation provides arms 1^a and 1^b. Channels 1^c and 1^d are formed in the arms 1^a and 1^b, respectively, by continuous lips 1^e and 1^f. The channel 1^c in the arm 1^a is adapted to receive the hanger member 2, and the channel 1^d in the arm 1^b is adapted to receive the key engaging member 3. Member 2 is provided with a clip 2^a adapted to engage the shank 4 of the door knob. Member 3 has a flat hook 3^a formed integral therewith which is adapted to receive the head 5^a of the key.

The stem 2^b of the member 2 is adjustable 75 in the arm 1^a, and the stem 3^b of the member 3 is likewise adjustable in the arm 1^b. When adjusted to suit existing conditions, or relative positions of key and knob shank, the several elements are held firmly in the desired relation to each other by set screws 6 and 7, the screw 6 clamping the member 2 and the screw 7 performing a like function with member 3.

The support 1 is preferably provided with 85 a tongue 1^g adapted to enter the key hole and thereby enhance the rigidity of the device when properly adjusted and applied to the door.

It will be seen that the device can be 90 readily adjusted to meet varying dimensions between knob shank and key hole, and also to accommodate keys of different lengths, and when properly applied and adjusted as shown in Fig. 1, the key 5 is retained in the lock by its engagement with the flat hook 3^a. The particular formation of the hook 3^a also 95 prevents the turning of the key in the lock by nippers or other instruments inserted from the opposite side of the door.

The improved device can be economically manufactured, being formed entirely of sheet metal stampings, with the exception of the set-screws, and when formed it provides a durable and reliable device for the 105 purpose set forth, that can be conveniently carried in the pocket.

Modifications may be made in the device as to minor details of design without affecting its mode of operation or departing from 110

the principle and scope of the invention, the limitation being governed by the appended claims.

What I claim and desire to secure by Letters Patent is.

1. A retainer for door keys, comprising a supporting bracket having a vertical and a longitudinal member, a member adapted to engage the shank of the door knob adjustably connected with the vertical bracket member, and a key retaining member adjustably connected with the longitudinal bracket member.
2. In a retainer for door keys, the combination of a supporting bracket provided with a vertical and a longitudinal leg, said legs having channels formed therein; a door knob shank engaging member adjustable in the vertical channel; and a key engaging member adjustable in the longitudinal channel.
3. In a retainer for door keys, the combination of a supporting bracket provided with a vertical and a longitudinal leg, said legs having channels formed therein; a door knob shank engaging member adjustable in the vertical channel; a key engaging member adjustable in the longitudinal channel; and means for holding said members in adjustment.

Copies of this patent may be obtained for five cents each, by addressing the "Commissioner of Patents, Washington, D. C."

4. In a retainer for door keys, the combination of a supporting bracket provided with a vertical and a longitudinal leg, said legs having channels formed therein; an adjustable member in the vertical channel; a clip on said member for engagement with the shank of the door knob; an adjustable member in the longitudinal channel; and a hook on the last named member for engagement with the door key.

5. In a retainer for door keys, the combination of a supporting bracket provided with vertical and longitudinal legs; a door knob shank engaging member adjustably connected with the vertical leg; a key engaging member adjustably connected with the longitudinal leg; and a tongue on said supporting bracket for engagement in the key hole of the door.

6. In a key retainer for door keys the combination of a supporting bracket; means for adjustably connecting said bracket with the shank of the door knob; a key engaging member adjustably connected with said bracket; and a tongue on said supporting bracket for engagement in the key hole of the door.

In testimony whereof I affix my signature.

CIRILL J. STEINER.
